UNITED STATES PATENT OFFICE.

JOHN C. KONRAD, OF NEW YORK, N. Y., ASSIGNOR TO CLARENCE
WAINRIGHT WOOD, OF SAME PLACE.

DESIGN FOR A BODY FOR DELIVERY-WAGONS.

SPECIFICATION forming part of Design No. 28,751, dated May 31, 1898.

Application filed February 19, 1898. Serial No. 670,977. Term of patent 7 years.

To all whom it may concern:

Be it known that I, JOHN C. KONRAD, a citizen of the United States of America, and a resident of the borough of Manhattan, in the city of New York and State of New York, have 5 invented and produced a new and original Design for a Body for Delivery-Wagons, of which the following is a specification, reference being had to the accompanying drawing, forming part thereof.

The figure of the drawing is a side view of the body of a delivery-wagon, showing said new and original design.

The leading or material feature of the present design is the shape or configuration of the side of the body at its front edge, as represented in the drawing and hereinafter described. Said shape or configuration at the front edge comprises an open recess *a* immediately below the top or roof of the body, connected above by two short concave curves *b* and *c* with a substantially horizontal underline *d* at the front of the roof, and connected below by a short concave curve *e* with a vertical line *f* in front of the seat portion. A raised border *1* is conformed eccentrically to the curvilinear shape of said recess *a*, and follows said curves and lines *b*, *c*, *e*, and *f*. Within the border *1* of the recess *a* it is provided with a crescent-shaped lining *2*, and in front of the latter with an edge bar or border *3*, such triple framing of said recess being in the general form of an ornamental "C" re-

versed. A bifurcate projection from the vertical portion of said border *1* is represented 35 at *g*. Said crescent-shaped lining *2* is represented as provided with horizontal lines to make it contrast with said border *1* and said edge bar *3*. The latter is represented as provided with recurved projecting extremities 40 and with a bilabiate or bifoliate central ornament and an ornamental attachment relieving the intersection of said curve *e*, and said front line *f* is represented at *4*. A raised border *5*, extending along the bottom of the 45 body from the lower end of said raised border *1*, follows the outline of a peculiarly-shaped arch *h* beneath the seat, and is provided thereat with an abutment projection *i* and a haunch projection *j* in front, rounded curves *k* and *l* 50 at haunch and abutment in rear, and a bilabiate or bifoliate inward projection *m* within the corner formed by said curve *l*. A side panel of irregular shape, behind said raised border *1* and above said raised border *5*, is 55 represented at *p*, and a penciled border-line on said panel is represented at *6*.

Having thus described said design, I claim as new and original and desire to patent under this specification—

The design for the body of a delivery-wagon, substantially as shown and described.

JOHN C. KONRAD.
